UNITED STATES PATENT OFFICE.

DANIEL M. HOIT, OF MORRIS, ASSIGNOR TO THE COLEMAN HARDWARE COMPANY, OF CHICAGO, ILLINOIS.

SPRING-HINGE.

SPECIFICATION forming part of Letters Patent No. 403,670, dated May 21, 1889.

Application filed July 2, 1888. Serial No. 278,866. (Model.)

To all whom it may concern:

Be it known that I, DANIEL M. HOIT, a citizen of the United States, residing at Morris, Grundy county, Illinois, have invented certain new and useful Improvements in Spring-Hinges, of which the following is a specification.

The object of my invention, in general terms, is to make a spring-hinge that will tend to hold a door, gate, shutter, or other object on which it is mounted closed until it is opened beyond a certain point, when it will tend to keep it closed; and my invention consists in the features and details of construction hereinafter described and claimed.

In the drawings, Figure 1 is a plan view of my improved hinge viewed from above; Fig. 2, a plan view of the same viewed from below; Fig. 3, a plan view of a modification viewed from above; Fig. 4, a side elevation of the hinge shown in Fig. 1; Fig. 5, a longitudinal vertical section taken in the line 5 5 of Fig. 1, looking in the direction of the arrows; Fig. 6, a transverse vertical section taken in the line 6 6 of Fig. 3, looking in the direction of the arrows; and Fig. 7, an end elevation of the ratchet shown in Fig. 6, looking in the opposite direction to that indicated by the arrows.

In the drawings, A A are the leaves of the hinge; B, the coiled spring; C, the axis around which the coiled spring is arranged; D, the knuckle at the end of such axis; E, a T-headed lever; F, a hook or lug to receive and guide the free end of the T-headed lever; G, a collar for the outer end of the spring; H, a collar for the inner end of the spring; I, a ratchet-wheel on such collar; J, an ear or lug through which the inner end of the axis of the coiled spring passes.

In making my improved spring-hinge I make two leaves of suitable form, which are provided with ears or lugs raised above or out of the plane of the hinge-leaves. These ears or lugs are intended to embrace or fit each other, so as to afford means of pivotally connecting the hinge-leaves together. They may be connected together by means of ordinary rivets, as shown in Fig. 3, or by means of pins or studs cast on two of the ears and passing through holes in the other ears intended

to receive them, as shown in Figs. 1 and 2. When the ears or lugs of the hinge-leaves are connected together by pins or studs cast thereon or attached thereto, I prefer to provide one of them with a tongue or projection at one side, (indicated by the letter T) and to provide the hole in which it is intended to be inserted with a slot, which I have indicated by the letter S. These features are particularly shown in Fig. 4 of the drawings. In inserting the pin or stud it must be turned to that position which will bring its tongue or projection in a line with the slot, when it may be inserted and turned as desired. This arrangement for pivotally connecting the ears or lugs of the hinge-leaves together, however, is only one of the various ways in which it may be done. As before suggested, common rivets, as shown in Fig. 3, will serve the purpose; but however connected together I term the pivotal points the "axis" of the hinge.

I prefer to provide one of the hinge-leaves with an inclosing barrel or case, as shown in several figures of the drawings. This barrel or case is intended to receive the coiled spring and protect it from rust or injury by the weather, or from the interference of children or curious persons. This case or barrel for inclosing the spring is not, however, essential to the construction and operation of my invention, and in the third figure of the drawings I have shown it as dispensed with and the spring exposed to view; but whether a barrel or case be employed or not the leaf is adapted and intended to receive a coiled spring located lengthwise of the leaf, by which I mean substantially at right angles to the axis of the hinge. This spring may consist of one or more coils of spring-wire of the size, strength, and elasticity desired. I have shown it as composed of a number of coils; but I wish to say here that the number of coils employed is a matter that can be varied at pleasure, and, if desired, less than one entire coil can be used. This spring is intended to be mounted upon or coiled around or partially around an axis, C. This axis passes through bearings or holes in both the inner and the outer end of the barrel, as shown particularly in Fig. 5 of the drawings, or, where the barrel or case is dispensed with, through holes or bear-

ings in the ears or lugs corresponding to the ends of the barrel or case, as shown in Fig. 3. The axis is provided near its outer bearing with a collar, G, which is mounted securely thereon and so as to rotate therewith. This collar may be prevented from rotation by providing it with a square or angular hole and making that portion of the axis on which it is mounted of a corresponding angular form.

The collar, as shown in the drawings, is provided with a notch or hole, as shown in Figs. 2 and 3, in which the outer end of the wire composing the coil-spring can be placed and held so that the end of the wire will be carried around with the rotation of the axis and collar in that direction which tends to coil and increase the tension of the spring. As this collar is principally intended to afford means for attaching the outer end of the spring-wire to its axis, so as to carry it around as the axis is turned and further coil or bend the spring, it is obvious that it may be entirely dispensed with and the end of the wire fastened in some convenient way to the axis, so as to be carried around as it is rotated, though I prefer to use the collar I have illustrated in the drawings and have described above. The other or inner end of the spring-wire is intended to be fastened in a notch or hole, which remains in the same relative position as the parts are operated. This notch or hole, as shown in Fig. 2, is made in the inner end of the barrel or case, though it is obvious that any arrangement may be adopted for securing the inner end of the wire which will hold it securely and non-rotatably as the other end is turned or coiled by the rotation of the spring-axis. If desired, the inner end of the spring may rest in a notch or hole in an adjusting-collar, H, as shown in Figs. 3 and 7. This collar is mounted rotatably on the spring-axis and is provided with a ratchet, and a pawl is pivoted on the inner edge of the ear or lug corresponding to the inner end of the barrel or case, though other means may be employed to lock or hold the adjusting-collar at whatever point it may be rotated on the spring-axis. When this arrangement is used, the tension of the spring may be adjusted from time to time, or as desired, by turning the collar H in the proper direction until a sufficient degree of tension has been secured, when it will be held in the desired position by the engagement of the pawl with the ratchet-teeth or by whatever locking devices may be employed. As the operation of my invention, however, does not depend upon the presence or absence of the adjusting-collar and locking devices, I do not desire to limit myself to their use, except in those combinations in which they are specifically claimed; and I may also say in this connection that the inner end of the spring-wire may be connected with the spring-axis, so as to be carried around with it, and the outer end held in a fixed position, if preferred. In

other words, it is immaterial which end of the spring-wire is held fixed and which end is carried around by the rotation of the spring- 70

The inner end of the axis of the spring is provided with a knuckle, D. This knuckle is furnished with two bearings, d d', which may be of greater or less distance apart, as may 75 be desired. They are intended to furnish the leverage points by which force may be applied to rotate the axis of the hinge and further bend or coil the spring. They should therefore be of such distance apart as will correspond to the power and tension of the spring intended to be bent or coiled by the turning of the axis. If the spring be light, these bearings may be close together; but if the spring is strong and powerful, so that considerable 80 leverage may be required to coil or bend it, they should be of greater distance apart. In this respect the leverage may be likened to that afforded by the hand-wheel or car-brakes operated by the brakeman, where the greater 85 diameter of the wheel the more leverage power it affords in operation. I then make a T-headed lever, E, the members of whose 90 T-head, as shown in the drawings, are of a proper length and size to rest in the bearings provided in the knuckle D. The position of this T-headed lever will be understood by reference to the drawings, where it is particularly shown in Fig. 2.

The members of the T-head engage with 100 the bearings in the knuckle at opposite sides of the axis, so that one of the members rests in the bearing on the underside of the knuckle and the other in the bearing on the upper side of the knuckle. It is obvious that when thus 105 engaged any turning of the lever will cause a turning of the axis in the bearings of whose knuckle the members of the T-head are arranged. It is intended, however, that the uncoiling power of the spring shall cause the 110 bearings in the knuckle to press against the respective members of the T-head with which they are engaged and hold them in close contact, so that one cannot rotate without the other and so that the rotation of the one will 115 cause the rotation of the other. To prevent the uncoiling power of the spring from rotating its axis and the T-headed lever beyond that point which will hold the hinge-leaves open or unfolded, the free end of the lever is 120 carried off to the opposite hinge-leaf at an angle, where it passes under or through a guide hook or hole, F, provided at one corner of the hinge-leaf, as shown in the drawings. This guide or hole is made in any convenient way, 125 although I have represented it in the form of a hook or lug extending up above the plane of the hinge-leaf and inclosing the free end of the lever.

I have described the members of the lever 130 as resting one in a bearing on the under side of the knuckle and the other in a bearing on the upper side of the knuckle. This arrangement is well shown in Fig. 2 of the drawings.

As there shown, the under side of one of the members and the upper side of the other are open or exposed. The member which is exposed on the under side is prevented from falling out by the torsional power of the spring operating through the arrangement of the lever at an angle to the axis of the spring, which brings the members against opposite sides of the bearings. While I have shown each of the members as exposed or open at one side, I do not wish to be understood as limiting myself to this construction, except in those claims where such arrangement may be specifically claimed, as it is obvious that one or even both of the members could be arranged in bearings which are closed or made in the form of holes, provided they are made sufficiently large to enable the ends of the members of the lever to properly turn or play in the folding of the hinge-leaves. I have also shown the hinge-leaves opening in but one direction, though it is obvious that the ears or lugs of the hinge-leaves may be so made and pivoted together as to permit the hinge to fold in either direction, and so make the hinge a reversible one, to accommodate either right or left hand doors. These various modifications will be sufficiently plain from an examination of the drawings without further minute description.

When I have made the parts as above described, I coil or bend the wire forming the spring as few or as many times about its axis as desired. The axis is arranged in its bearings on one of the hinge-leaves, and one end of the wire connected so as to rotate with it, and the other end of the wire fixed so that it will be held without rotating. I then turn the knuckle on the inner end of the axis until the spring-wire has been bent or coiled to that degree of tension required, and so that the bearings on the knuckle which is intended to be in the angle formed by the axis of the spring and the axis of the lever shall be above the plane of such axes and the tendency of the uncoiling power of the spring-wire exerted in that direction which would carry such bearing below such axes. I then, while holding the knuckle in this position, insert the members of the T-head of the lever in their respective bearings and slip the free end of the lever through the hole or guide intended for it in the other leaf of the hinge and pivotally connect their ears in condition for use. The tendency of the spring will be to uncoil and rotate its axis and the T-headed lever with which it is engaged; but as that bearing which is in the angle formed by the axis of the spring and the axis of the lever is, as above explained, above the plane of these axes, it is obvious that the spring cannot rotate the parts in that direction as long as the free end of the lever is held by the hole or guide F at an angle. It can only rotate further in that direction by bringing the axis of the lever and the axis of the spring in a line, which is prevented by the hole or

guide F. The limit of rotation in the direction which will open the spring is therefore reached at that point at which the spring is 70 opened or its leaves unfolded and in the same plane. No such obstacle exists, however, to rotation in the opposite direction, and as the hinges of the leaves are folded or turned back toward each other the lever is 75 carried with them, and, as it is set at an angle so that it cannot fold back like the leaves of the hinge, it is forced to rotate, and with it rotate the axis of the spring, by which the spring is further bent or coiled and its tension increased. This operation continues until the hinge-leaves have been opened toward each other to or about to one-quarter of a revolution and the spring-axis rotated to or about to one-quarter revolution, when the lever begins to approach the axis of the hinge, but so as to form an acute instead of an obtuse angle, and to permit the spring axis to reverse the direction of its rotation. The moment the lever has passed the line that 85 brings it at a right angle to the axis of the spring the uncoiling power of the spring is immediately exerted to bring it to an acute angle, while as soon as it passes the right-angle line in the other direction the tendency 90 of the spring is to bring it to an obtuse angle. In this way the leaves of the spring are held open or unfolded until the door or gate to which they are attached has been opened about ninety degrees, when the spring immediately 95 begins to exert its power to bring the gate or door back another ninety degrees. The spring therefore operates to hold the gate or door closed until opened to a certain point by the application of positive force and then to hold 100 it open until it is closed to a certain point by the application of positive force.

What I regard as new, and desire to secure by Letters Patent, is—

1. In a spring-hinge, the combination of 110 two leaves of suitable form provided with ears or lugs pivotally connected together at points outside of the plane of the hinge-leaves, a spring-axis arranged in bearings on one of the hinge-leaves and rotatable therein, 115 a spring-wire coiled or bent around or partially around the spring-axis and having one of its ends held in a fixed position and the other of its ends carried around with the rotation of the spring-axis, and a lever engaging 120 at one end with one end of the spring-axis and having its other end connected with the other hinge-leaf, whereby it is rotatable on its longitudinal axis by the folding of the hinge-leaves in that direction which rotates 125 the spring-axis and further coils or bends the spring-wire, substantially as described.

2. In a spring-hinge, the combination of 130 two leaves of suitable form provided with ears or lugs pivotally connected together at points outside of the plane of the hinge-leaves, a spring-axis arranged in bearings on one of the hinge-leaves and rotatable therein, a spring-wire coiled or bent around or partially

around the spring-axis and having one of its ends held in a fixed position and the other of its ends carried around with the rotation of the spring-axis, and a lever arranged at an angle to the spring-axis when the hinge-leaves are open or unfolded and engaging at one of its ends with one end of the spring-axis and having its other end connected with the other hinge-leaf, whereby it is rotatable on its longitudinal axis by the folding of the hinge-leaves in that direction which rotates the spring-axis and further coils or bends the spring-wire until the lever reaches a point at right angles to the spring-axis, when the further folding of the hinge-leaves permits the spring-axis to be rotated in that direction which uncoils or unbends the spring-wire, substantially as described.

3. In a spring-hinge, the combination of two leaves of suitable form provided with ears or lugs pivotally connected together at points outside of the plane of the hinge-leaves, a spring-axis arranged in bearings on one of the hinge-leaves and rotatable therein, a spring-wire coiled or bent around or partially around the spring-axis and having one of its ends held in a fixed position and the other of its ends carried around with the rotation of the spring-axis, and a lever arranged at an angle to the spring-axis when the hinge-leaves are open or unfolded and engaging at one of its ends with one end of the spring-axis at a point within the angle and above the plane of the spring-axis and lever when the hinge-leaves are open or unfolded and having its other end connected with the other hinge-leaf, whereby it is rotatable on its longitudinal axis by the folding of the hinge-leaves in that direction which rotates the spring-axis and further coils or bends the spring-wire, substantially as described.

4. In a spring-hinge, the combination of two leaves of suitable form provided with ears or lugs pivotally connected together at points outside of the plane of the hinge-leaves, a spring-axis arranged in bearings on one of the hinge-leaves and rotatable therein and provided at one end with bearings on opposite sides of the axis, a spring-wire coiled around or partially around the spring-axis and having one of its ends held in a fixed position and the other of its ends carried around with the rotation of the spring-axis, and a lever having lugs on one end adapted to engage with the bearings on the end of the spring-axis and having its other end connected with the other hinge-leaf, whereby it is rotatable on its longitudinal axis by the folding of the hinge-leaves in that direction which rotates the spring-axis and further coils or bends the spring-wire, substantially as described.

leaves in that direction which rotates the spring-axis and further coils or bends the spring-wire, substantially as described.

5. In a spring-hinge, the combination of two leaves of suitable form provided with ears or lugs pivotally connected together at points outside of the plane of the hinge-leaves, a spring-axis arranged in bearings on one of the hinge-leaves and rotatable therein and provided at one end with bearings on opposite sides of the axis and adapted to engage the upper side of one lug and the lower side of the other lug of a lever and leave the opposite sides open or exposed, a spring-wire coiled around or partially around the spring-axis and having one of its ends held in a fixed position and the other of its ends carried around with the rotation of the spring-axis, and a lever having lugs on one end adapted to engage with the bearings on the end of the spring-axis at the opposite sides thereof on the upper side of one lug and the under side of the other lug and leave the opposite side open or exposed, and having its other end connected with the other hinge-leaf, whereby it is rotatable on its longitudinal axis by the folding of the hinge-leaves in that direction which rotates the spring-axis and further coils or bends the spring-wire, substantially as described.

6. In a spring-hinge, the combination of two leaves of suitable form provided with ears or lugs pivotally connected together at points outside of the plane of the hinge-leaves, a spring-axis arranged in bearings on one of the hinge-leaves and rotatable therein, an adjusting-collar mounted on the spring-axis and rotatable thereon and arranged to be locked or held at any desired position, a spring-wire coiled or bent around or partially around the spring-axis and having one of its ends connected with the adjusting-collar and the other of its ends carried around with the rotation of the spring-axis, whereby the rotation of the collar on the spring-axis increases or diminishes the tension of the spring-wire, and a lever engaging with one end of the spring-axis arranged at an angle thereto and having its other end connected with the other hinge-leaf, whereby it is rotatable on its longitudinal axis by the folding of the hinge-leaves in that direction which rotates the spring-axis and further coils or bends the spring-wire, substantially as described.
